UNITED STATES PATENT OFFICE.

WILLIAM T. McLAUGHLIN, OF BOSTON, MASSACHUSETTS.

CUSHIONED HEEL.

Application filed February 20, 1923. Serial No. 620,202.

To all whom it may concern:

Be it known that I, WILLIAM T. McLAUGHLIN, a citizen of the United States, residing at Boston, in the county of Suffolk 5 and State of Massachusetts, have invented new and useful Improvements in Cushioned Heels, of which the following is a specification.

The chief object of this invention is to 10 provide a shoe heel having a resilient cushioning member composed in part of an elastic rubber insert, secured in a heel-shaped body and forming a part of the tread face of the latter, and in part, of a metal spring 15 anchored in said insert, and so projecting therefrom that a portion of the spring is enclosed in the body, at one side of, and above the insert, the arrangement being such that the insert and the spring collectively 20 cushion an area of the body greater than the area of the insert, the major portion of the spring being free to rise and fall without obstruction by the insert and by any other portion of the spring.

25 I attain the above mentioned and other related objects by the improvements hereinafter described and claimed.

Of the accompanying drawings forming a part of this specification,—

30 Figure 1 is a perspective view of the resilient cushioning member.

Figure 2 is an edge view of the same.

Figure 3 is a section on line 3—3 of Figure 1.

35 Figures 1, 2 and 3 are considerably enlarged.

Figure 4 is a bottom plan view of a heel embodying the invention, including a heel-shaped body and the resilient cushioning member shown by Figures 1, 2 and 3.

40 Figure 5 is an enlarged fragmentary section on line 5—5 of Figure 4.

The same reference characters indicate the same parts in all the figures.

45 12 represents a heel-shaped body which, in a heel constituting the preferred embodiment of the invention, is made entirely of elastic rubber, or a composition containing rubber, and such as is commonly used in

50 the manufacture of so-called rubber heels. Between the top face 12^a and the tread face 12^b of the body, is a cavity 13, the top and bottom sides of which are spaced apart for a purpose hereinafter described. 14

55 15 represents an elastic rubber insert, secured in the body 12, and forming a part of the

tread face thereof, one end of the insert preferably projecting below the tread face 12^b as shown by Figure 5.

15 represents a metal spring, constituting 60 an incomplete convolution of a helix. Said spring has a lower end portion 15^a, anchored in the insert 14, preferably by being embedded in the latter, as shown by Figures 1, 2 and 3, before the rubber is 65 vulcanized, the subsequent vulcanization of the rubber causing the lower end portion 15^a to adhere firmly to the insert. The upper end portion 15^b of the spring is located above and at one side of the insert, and 70 bears on the upper side of the cavity 13. The lower side of the cavity is spaced from the spring portion portion 15^b so that said portion is free to be depressed by downward pressure on the top face of the heel, 75 and supplements the spring action of the insert 14.

The above described parts are assembled before the material of the body 12 and insert 14 are vulcanized, the body and the insert being subsequently united by a vulcanization process.

The major portion of the spring is outside the insert 14, and is free to rise and fall without obstruction by the insert and 85 by the anchored end portion 15^a. There is therefore no interference between the free end portion and the anchored end portion, such as would be caused if the spring were composed of complete convolutions, as in an 90 ordinary helical spring.

It will be seen that the insert 14 and spring 15 collectively constitute a heel cushioning member adapted to cushion an area 95 of the body greater than the area of the insert, so that the heel possesses in said area a desirable degree of resilience.

I prefer to arrange the spring as shown by Figure 4, with its ends relatively near the portion of the outside edge of the body 100 which is subjected to greatest pressure in the act of walking, the spring ends being at the outer margin of the spring, and relatively near the rear portion of the outside edge of the body, the major portion of the 105 spring being farther from said edge portion. By this arrangement I am enabled to utilize the resilience of the spring 15 to the best advantage.

Instead of using a single cushioning member which includes a spring 15, having a relatively large diameter, as shown by Fig-

ure 4, I may use a plurality of said members, each including a spring of smaller diameter.

The described cushioning member may be employed with a body which is composed of leather, or other material not possessing the elasticity of a rubber heel.

The insert may be composed of a non-metallic material which does not possess the elasticity or compressibility of the material of a rubber heel, and has a desirable frictional quality. For example, the insert may be composed of cotton duck or canvas, frictioned with rubber and formed into a cylindrical or other suitable shape, in which case the cushioning action is due wholly or mainly to the metal spring.

It will be seen that the spring 15 has the form of an ordinary spring washer, composed of an incomplete convolution and adapted to rise and fall at one end without obstruction by the other end. If the spring were helical and composed of more than an incomplete convolution, the yielding of its free end would be obstructed by a convolution or convolutions below it.

I claim:

1. A heel-cushioning member composed of a non-metallic insert adapted to be secured in the body of a heel, and a metal spring constituting an incomplete convolution of a helix, having an end portion anchored in said insert, and a major portion outside and

projecting laterally from the insert and free to rise and fall without obstruction by the insert and by the anchored end portion.

2. A heel comprising a body having a cavity between its tread and top faces, and a cushioning member composed of a non-metallic insert secured in the body, and a metal spring constituting an incomplete convolution of a helix, having an end portion anchored in the insert, and a major portion located outside the insert, projecting laterally from the insert into said cavity, and free to rise and fall without obstruction by the insert and by the anchored end portion.

3. A heel comprising a resilient body, and a cushioning member composed of a non-metallic insert secured in the body, and a metal spring constituting an incomplete convolution of a helix, having an end portion anchored in the insert, and a major portion located outside the insert, projecting laterally from the insert into the body, and free to rise and fall without obstruction by the insert and by the anchored end portion.

4. A heel substantially as specified by claim 3, the said spring being arranged with its ends relatively near the portion of the outside edge of said body which is subjected to the greatest pressure and wear.

In testimony whereof I have affixed my signature:

WILLIAM T. McLAUGHLIN
